GAME BOARD

Virgil S. Packard, San Francisco, Calif.

Application March 1, 1949, Serial No. 1,160

Term of patent 7 years

(Cl. D34—5)

To all whom it may concern:

Be it known that I, Virgil S. Packard, a citizen of the United States, residing at 20 Monroe Street, San Francisco 8, in the county of San Francisco and State of California, have invented a new, original, and ornamental Design for Game Board, of which the following is a specification, reference being had to the accompanying drawing, forming a part thereof.

Fig. 1 is a top plane view of a game board showing my new design.

Fig. 2 is sectional view of the game board shown in Fig. 1.

The bottom side of the game board is plain. The shading indicates differences in color only.

The dominant features of my design reside in that portion shown in full lines of the drawing.

I claim:

The ornamental design for a game board, shown and described.

VIRGIL S. PACKARD.
